United States Patent

Des. 236,051
Patented July 29, 1975

236,051

HOLDER FOR VASES AND THE LIKE

Victor E. Opincar, Sr., 7 Terrace, Lido Park,
Newport Beach, Calif. 92660

Filed Nov. 29, 1973, Ser. No. 419,917

Term of patent 14 years

Int. Cl. D11—02

U.S. Cl. D6—114

FIG. 1 is a perspective view of a holder for vases and the like embodying my new design;

FIG. 2 is a bottom plan view thereof;

FIG. 3 is a front elevational view thereof; and

FIG. 4 is a side elevational view thereof showing the side which is not visible in FIG. 1.

I claim:

The ornamental design for a holder for vases and the like, substantially as shown.
